Atty.

UNITED STATES PATENT OFFICE.

WILLIAM H. DOANE, OF CINCINNATI, OHIO.

WOOD-WORKER.

SPECIFICATION forming part of Letters Patent No. 392,591, dated November 13, 1888.

Application filed July 9, 1888. Serial No. 279,370. (No model.)

To all whom it may concern:

Be it known that I, WILLIAM H. DOANE, a citizen of the United States, residing at Cincinnati, Ohio, have invented new and useful 5 Improvements in Wood-Workers, of which the following is a specification.

My invention relates to a class of "wood-workers" in which the cutter-arbor is carried in three bearings—two terminal beyond the 10 cutter-head and driving-pulley, respectively, and one intermediate between the cutter-head and driving-pulley, its object being to provide a construction by which the cutter-arbor may be shifted to adjust the cutter laterally in relation to the work, yet at the same time preserve 15 the necessary rigidity of the arbor and prevent a ragged or unequal action of the cutter-head.

In another application of even date here-with I have shown a construction to this end, 20 in which the two cutter-head journal-bearings, or all three bearings, are rigid projections of an adjustable box-frame with long sliding surfaces in different planes for obtaining rigidity; but in the present invention I seek to avoid 25 the expense of such construction and to accomplish the desired end by making the bearings independent and preserving one of the two rear bearings absolutely fixed to the bed-frame, while the other is adjustable to shift the 30 arbor and cutter, all as hereinafter more fully set forth.

Mechanism illustrating my invention is exhibited in the following drawings, in which—

Figure 1 is a cross-elevation showing a construction in which the outer or terminal bearings are fixed and the center bearing is alone adjustable; Fig. 2, a rear elevation; Fig. 3, a plan view of the same machine; and Fig. 4, a partial cross-elevation of a construction in 40 which the central bearing is fixed and the outer bearing is adjustable.

Referring now to the drawings, in which the letters of reference indicate the parts herein described, A' designates the supporting frame 45 or bed of the machine, and A B C designate, respectively, the rear, central, and front bearings of the cutter-mandrel E, the latter carrying the cutter-head D and drive-pulley P. The cutter-head D operates in the interval between 50 two work-carrying platens, F F', which in the present case are shown mounted upon support-

ing guide-blocks G H, by which they are adjustable. These features need not be further described here, as they constitute no part of my present invention, and are introduced 55 merely to define the class of machines to which my invention is applied.

The rear bearing, A, Figs. 1, 2, and 3, is an upward fixed extension of the base-frame or bed A' of the machine. The front bearing, C, 60 is also relatively fixed in position, but is detachable from the bed-frame, being held by a screw-clamp, C', operated by a handle or lever, C''. It may be removed from its position on the bed-frame and slipped from the arbor 65 endwise when necessary to remove the cutter-head.

The arbor is arranged to be shifted longitudinally in its front and rear terminal bearings as impelled by the central bearing, B, 70 which is horizontally adjustable upon the bed-frame A' in gibbs B'. The central bearing acts as a shifting-clutch by engagement at one side against the hub of the drive-pulley, and at the other against a collar, E', secured upon the 75 arbor, being at the same time a bearing for the arbor and relatively rigid when stationary. The bearing B is formed with an enlarged base, B'', carried in planed ways upon the bed-frame, and secured in its sliding bearing by 80 gibbs B'.

Centrally beneath the bearing B projects a tongue, J, engaging an adjusting-screw, I, carried outward in a suitable socket in the rear wall of the bed-frame, and provided with a 85 hand-wheel, I', by which means the adjustment is made.

It will be observed as the leading principle of the construction that the cutter-arbor is retained in two relatively fixed bearings at all 90 times, while the third bearing is alone adjustable. The advantage of this is that the proper alignment of the arbor is preserved and is practically independent of any lost motion in the intermediate or movable bearing, because 95 of the fixedness of the other bearings. As an alternative embodying the same principles, and on some accounts preferable, I have shown in Fig. 4 a construction in which the bearings B and C are fixed, while the rear terminal 100 bearing, A, is made adjustable in the manner already described. The fixed bearings are

thus brought closer together and in such relations to the cutter as to preserve the utmost rigidity while in action.

I claim as my invention and desire to secure 5 by Letters Patent of the United States—

In a wood-worker, in combination with the cutter-arbor and a detachable but relatively fixed front bearing for the same, two other independent bearings, one intermediate between the cutter-head and drive-pulley and one terminal beyond the drive-pulley—one of

which supplemental bearings is positively fixed and the other adjustable to shift the arbor and cutter-head laterally in relation to the work, substantially as set forth.

In testimony whereof I have hereunto set my hand in the presence of two subscribing witnesses.

WILLIAM H. DOANE.
